US00D529756S

(12) **United States Design Patent** (10) **Patent No.:** **US D529,756 S**
Boss et al. (45) **Date of Patent:** **** Oct. 10, 2006**

(54) **BUNNY BAKING PAN**

(75) Inventors: **Virginia M. Boss**, Minneapolis, VA (US); **Phillip L. Brookshire**, Cincinnati, OH (US); **Patricia A. Schweitzer**, Glen Allen, VA (US); **Amy M. Standard**, Manakin Sabot, VA (US); **Monica Stautner Nichols**, Richmond, VA (US); **Jennifer Danich O'Flynn**, Richmond, VA (US); **Bruce Robbins**, Richmond, VA (US)

(73) Assignee: **Alcoa, Inc.**, Pittsburgh, PA (US)

(**) Term: **14 Years**

(21) Appl. No.: **29/252,573**

(22) Filed: **Jan. 25, 2006**

(51) **LOC (8) Cl.** **07-02**

(52) **U.S. Cl.** **D7/359**

(58) **Field of Classification Search** ..... D7/323, D7/354, 356, 357, 359, 360, 409, 500, 552, D7/554.1, 554.2, 554.3, 554.4, 556; D9/456; D15/90; 99/422, 425, 426, 428, 430, 432, 99/439-442, 444, 446, DIG. 15; 206/557, 206/561-564; 220/405, 445, 447, 469, 500, 220/507, 508, 553, 555, 575, 626

(57) **CLAIM**

The ornamental design for a bunny baking pan, as shown and described.

DESCRIPTION

FIG. 1 is a top perspective view of the bunny baking pan, showing the present design;
 FIG. 2 is a top plan view of the present design;
 FIG. 3 is a bottom plan view of the present design;
 FIG. 4 is a left side elevation view of the present design;
 FIG. 5 is a right side elevation view of the present design;
 FIG. 6 is a rear elevation view of the present design; and,
 FIG. 7 is a front elevation view of the present design.
